UNITED STATES PATENT OFFICE

WALTER S. BAYLIS, OF LOS ANGELES, CALIFORNIA, ASSIGNOR, BY MESNE ASSIGNMENTS, TO FILTROL COMPANY OF CALIFORNIA, OF LOS ANGELES, CALIFORNIA, A CORPORATION OF CALIFORNIA

PROCESS OF TREATING CRUDE OIL OF THE PENNSYLVANIA TYPE

Application filed November 12, 1927. Serial No. 232,739.

My invention relates to the art of refining petroleum. Petroleum comprises a mixture of a large number of hydrocarbons, the boiling points of which extend over quite a large range of temperatures. This permits the petroleum to be divided by fractional distillation into a number of well known petroleum products, each of which comprises a group of said hydrocarbons, the boiling points of which are grouped fairly close together. Included in such products and named in order of decreasing boiling points are the following: tar, paraffin, grease, lubricating oil, distillate, kerosene, and gasoline.

In this fractional distillation there is usually a certain amount of decomposition of the hydrocarbons into carbenes, asphaltenes, and unsaturated hydrocarbons which discolor the product and which must be removed in order for the product to be marketable. It is common practice to accomplish this by treating the refined product successively with sulphuric acid and caustic soda. The acid and alkali treatment effects the desired purpose but produces large quantities of sludge or soapy substance which result from chemical union between the petroleum product being refined and the chemicals. Thus, considerable quantities of the product being refined are wasted.

It is an object of my invention to provide a process for removing impurities from a petroleum product without the formation of sludge.

Moreover, the cost of the chemicals used in the acid and alkali process is considerable and it is correspondingly an object of my invention to provide a process of purifying a petroleum product in which this expense is substantially eliminated.

It has been previously known that certain impurities can be removed from petroleum products after these products had been formed from crude petroleum by fractional distillation by the use of a suitable adsorptive agent such as acid-treated earth. The application of such adsorptive agent in the purifying process has been made after the product to be purified had been condensed and cooled. The effectiveness of the adsorp-

tive agent when applied in this manner is quite low.

It is therefore a further object of my invention to provide a process of purifying petroleum products with an adsorptive agent in which the effectiveness of the latter is materially increased.

While the process of my invention may be used in treating many different petroleum products, it is best adapted for use in refining lubricating oil from a crude petroleum which does not contain tar and asphalt.

The process of my invention is particularly adaptable to the treatment of crude oils such as the paraffin base Pennsylvania oil which has no tar or asphalt content and will be described in connection with treating such a paraffin base oil.

Further objects and advantages will be made manifest in the following description and in the accompanying drawing in which an apparatus suitable for carrying out the method of my invention is diagrammatically illustrated.

Referring specifically to the drawing, the apparatus of my invention includes an agitator 12, a pump 13, a series of heat exchangers 14, a pipe still 15, an atmospheric column 16, a cooler 17, a hydraulic pump 18, and filter press 19.

Leading from a suitable source of supply of paraffin base and crude oil and discharging into the agitator 12 is a crude oil supply pipe 36. Also discharging into the upper end of the agitator 12 is an adsorptive-material-feed pipe 37. Disposed within the agitator 12 is an agitating rotor 38 which is adapted to be rotated in any suitable manner as by the gears 39. Connecting the lower end of the agitator 12 with the in-take of the pump 13 is a pipe 40, while connecting the discharge end of the pump 13 with the in-take end of the series of heat exchangers 14 is a pipe 41. Connected with the pipe 41 at an elbow thereof is a steam pipe 42 having a valve 43. Connecting the outlet end of the series of heat exchangers 14 with the in-take end of the pipe still 15 is a pipe 45. The pipe still 15 is heated in any suitable manner as by fuel supplied by a burner 46. The discharge

end of the still 15 is connected to an intermediate portion of the atmospheric column 16 by a pipe 48. Beneath the point at which the pipe 48 enters the column 16, a series of baffle plates 49 and 50 is disposed in alternating relation so that any liquid discharged through the pipe 48 into the column 16 must pass in a circuitous route from the point of discharge to the bottom of the column 16.

Disposed in the atmospheric column 16 above the point at which the pipe 48 connects thereto are pairs 55 of baffle plates 49 and 50. These pairs 55 are positioned in spaced relation so as to make room between adjacent pairs of collector pans 56. Each of the collector pans 56 is connected by a pipe 57 to one of the heat exchangers 14 from which pipes 58 lead to suitable distillate storage tanks. Leading from the upper end of the atmospheric column 16 is a gasoline vapor line 60. Connecting the lower end of the atmospheric column 16 to the inlet end of the cooler 17 is a pipe 61. Connecting the discharge end of the cooler 17 to the inlet end of the pump 18 is a pipe 62 into which a solvent pipe 63 connects. The discharge end of the pump 18 is connected to the filter press 19 by a pipe 64. The filter press 19 may be any suitable type of press, but it is preferably a Sweetland press. Leading from this press is a liquor discharge pipe 65.

The operation of the apparatus above described in carrying out the process of my invention is as follows:

The process is designed to be continuous and a continuous supply of crude oil is therefore fed through the pipe 36 into the agitator 12. At the same time a continuous supply of a suitable adsorptive agent, which is preferably the acid-treated clay known to the trade as "Filtrol" but which may be any of the other well known adsorptive clays, is fed into the agitator 12 through the pipe 37. The agitator rotor 38 is rotated constantly so as to mix the crude oil and the adsorptive agent as these are fed into the agitator 12. The mixture of crude oil and adsorptive agent is drawn from the bottom of the agitator 12 through the pipe 40 by the pump 18 and discharged through the pipe 41 into the upper end of the series of heat exchangers 14. At this point, the valve 43 may be opened and steam forced into the mixture so as to raise the temperature of the mixture and accelerate any adsorptive tendency which the adsorptive agent may have on the crude oil as the temperature of the mixture is gradually raised in its passage through the series of heat exchangers 14.

The mixture usually enters the first of the heat exchangers 14 at a temperature of approximately 240° F. and leaves the last of the heat exchangers 14 through which it passes at a temperature of approximately 410° F.

The mixture is then conducted through the

pipe 45 to the pipe still 15, where it is raised to a temperature of substantially 750° F., at which temperature it is discharged from the pipe 48 into the atmospheric column 16. The mixture, entering the column 16, flows down through a circuitous path over the baffle plates 49 and 50 and releases all of the lighter fractions of the crude oil so that the residuum which collects in the lower end of the column 16 comprises a mixture of fractions which is termed cylinder stock and which has an average density of 26° Bé.

The various fractions of crude oil which pass upward through the column 16 in the form of vapors are condensed and cooled in the various pans 56, and flowing outward through the heat exchangers 14, effect a rise of the temperature of the crude oil and adsorptive-agent mixture as previously mentioned. Any gasoline vapor which is not condensed in the upper of the pans 56 passes from the column 16 through the gasoline vapor line 60 to a suitable condenser, not shown.

The various fractions thus condensed in the column 16, in order of decreasing boiling points, may include the following:

Wax slop	B. P. 650° F.
Wax distillate	B. P. 600° F.
Gas oil	B. P. 550° F.
Mineral seal	B. P. 500° F.
Kerosene	B. P. 425° F.

The cylinder stock which collects in the lower end of the column 16 flows through the cooler 17 and the pipe 62 to the pump 18. At this time a suitable solvent is introduced through the pipe 63 into the cylinder stock so that it may be handled more easily by the pump 18 and filter 19. The pump 18 forces the diluted cylinder stock through the pipe 63 into the filter press 19 which retains the adsorptive clay and permits the purified cylinder stock to be discharged through the pipe 65 which conducts it to a suitable place of storage. When a sufficient amount of cake has been formed in the filter press 19, the flow of mixture through this filter press is stopped and switched to another similar filter press held in readiness for this purpose. The cake in the filter press 19 is then washed with a suitable solvent so as to remove any of the remaining cylinder stock from the cake. Suitable provision may also be made for blowing the cake in the press with air and steam after removing the retained oil so as to drive out the excess of solvent and dry the cake. Thereafter the filter press is opened and the cake removed and conveyed by any suitable means, such as a belt conveyor, to the reactivating house where the clay is reactivated so as to again be suitable for use in the above described process.

As stated above, this process has been particularly successful with the use of "Filtrol",

which is a product that has been chemically treated so that there are no elements therein to cause any chemical reaction when acid is added to it. Therefore, no sulphates are formed as is the case when acid is added to 5 a natural or untreated earth. When "Filtrol" is used as the adsorptive agent, it is possible to add a slight amount of acid in the reactivating process so that the "Filtrol" acts as a carrier for the acid in an unaltered 10 state. Thus, due to the enormous surfaces in the "Filtrol" on which the acid is carried in a thin film, there is very powerful action on the oil, even when an extremely small amount of acid has been added to the "Filtrol".

15 Another great advantage of using the acid in this manner is that it acts upon the oil without being given up by the "Filtrol" so that neutralization of the final oil product is unnecessary.

20 In addition to the advantages of my process above noted, the submitting of the crude oil to the complete fractionating process in the presence of the acidified adsorptive agent purifies the oil by removing asphaltenes and 25 unsaturated hydrocarbons which form in the stills 10 and 15 while the oil is being refined.

It is also desired to point out that the 30 impure substances are absorbed by the adsorptive clay before the vapors are discharged from the mixture of oil and clay in the column 16, so that fractions condensed in the pans 56 of the column 16 are already purified and further treatment of these is therefore 35 unnecessary.

I claim as my invention:

1. The method of refining crude oil for the production of lubricating stock therefrom which comprises mixing decolorizing clay with the oil, passing the resultant mixture 40 through a heating zone and heating the same to a temperature sufficient to vaporize lighter fractions of the crude oil, introducing the mixture to a fractionating zone at a point substantially above the bottom thereof whereby 45 unvaporized portions of the mixture descend toward the bottom of said fractionating zone and released vapors ascend toward the top thereof, condensing heavier fractions of the released vapors in the portion of said fractionating zone above the point of introduction of the mixture thereto, separately withdrawing the condensed fractions from the fractionating zone, removing lighter fractions of the released vapors from the top of 50 said fractionating zone and subjecting the same to condensation, withdrawing the mixture of unvaporized lubricating stock and clay from the bottom of said fractionating zone, and separating the clay from said lubricating stock.

2. The method of refining crude oil for the production of lubricating stock therefrom which comprises mixing decolorizing clay with the oil, passing the resultant mixture

through a heating zone and heating the same to a temperature sufficient to vaporize lighter fractions of the crude oil, introducing the mixture to a fractionating zone at a point substantially above the bottom thereof whereby unvaporized portions of the mixture descend toward the bottom of said fractionating zone and released vapors ascend toward the top thereof, condensing fractions of the released vapors heavier than gasoline 70 in the portion of said fractionating zone above the point of introduction of the heated mixture thereto, separately withdrawing the condensed fractions from the fractionating zone, removing gasoline vapors from the top of said fractionating zone and subjecting the same to condensation, withdrawing the mixture of unvaporized lubricating stock and clay from the bottom of said fractionating zone, and separating the clay from said lubricating stock.

3. The method of refining hydrocarbon oil for the production of lubricating stock therefrom which comprises mixing decolorizing clay with the oil, passing the resultant mixture through a heating zone and heating the same sufficiently to vaporize lighter fractions of the oil, introducing the mixture to a separating zone at a point substantially above the bottom thereof, passing the mixture downwardly toward the bottom of said separating zone in relatively thin layers to assist the release of vapors therefrom, condensing released vapors in the portion of said separating zone above the point of introduction of the mixture thereto, separately withdrawing condensed vapors from the separating zone, removing the mixture of unvaporized lubricating stock and clay from the lower portion of said separating zone, and separating the clay from said lubricating stock.

In testimony whereof, I have hereunto set my hand at New York, New York, this 3rd day of November, 1927.

CERTIFICATE OF CORRECTION.

Patent No. 1,788,654.

Granted January 13, 1931, to

WALTER S. BAYLIS.

It is hereby certified that error appears in the printed specification of the above numbered patent requiring correction as follows: Page 3, after line 35, insert the following paragraph:-

A novel and very important feature of my invention is thus seen to be the treatment with an adsorptive agent of the oil being distilled in both its liquid and vapor phases. Another novel feature of importance is treating these liquid and vapor phases as they are interchanging with each other by alternate vaporization and condensation. The purification of the various products into which the oil is divided is thus accomplished concurrently with the distillation and with an efficiency and purity of product hitherto unknown.;

and that the said Letters Patent should be read with this correction therein that the same may conform to the record of the case in the Patent Office.

Signed and sealed this 24th day of February, A. D. 1931.
